UNITED STATES PATENT OFFICE.

WILLIAM L. MANN, OF ST. JOSEPH, MISSOURI.

DESIGN FOR A VEHICLE SIGNAL LAMP.

Application filed April 17, 1922. Serial No. 1,817. Term of patent 7 years.

To all whom it may concern:

Be it known that I, WILLIAM L. MANN, a citizen of the United States, residing at St. Joseph, in the county of Buchanan and State of Missouri, have invented a new, original, and ornamental Design for Vehicle Signal Lamp, of which the following is a specification, reference being had to the accompanying drawing, forming part thereof.

The figure is a front view of a vehicle signal lamp showing my new design.

I claim:

The ornamental design for a vehicle signal lamp as shown.

WILLIAM L. MANN.
